[57] CLAIM

The ornamental design for a grip held data entry computer having an automatic identification reader, as shown and described.

DESCRIPTION

FIG. 1 is a perspective view of a grip held data entry computer having an automatic identification reader showing our new design;

FIG. 2 is a front elevation thereof;

FIG. 3 is a top plan view thereof;

FIG. 4 is a rear elevation thereof;

FIG. 5 is a bottom plan view thereof;

FIG. 6 is a left side elevation thereof; and,

FIG. 7 is a right side elevation thereof.

The broken lines are shown in the views for illustrative purposes only and form no part of the claimed design.
